UNITED STATES PATENT OFFICE.

E. JOHN M. BECKER, OF NEW YORK, N. Y., ASSIGNOR TO ADAM KELLER,
OF SAME PLACE, AND JOHN C. DOWNING, OF NEWARK, N. J.

BRACELET.

SPECIFICATION forming part of Letters Patent No. 247,876, dated October 4, 1881.

Application filed July 27, 1881. (No model.)

To all whom it may concern:

Be it known that I, E. JOHN M. BECKER, of New York, in the county and State of New York, have invented certain new and useful 5 Improvements in Bracelets and like articles, of which the following is a specification.

These improvements relate particularly to bracelets which are composed of two parts, hinged together and actuated by a spring to 10 cause them to close and remain closed upon the arm.

The object of the improvements is to provide a spring for such a bracelet in a simple manner.

15 To this end the improvements consist in the combination, in a bracelet or analogous article, of two parts, one of which comprises two sections, either or both being resilient, and which are pivoted or hinged to the other part 20 at different positions in the length of the bracelet, whereby I produce a very simple bracelet, the parts of which, after being opened, will automatically close and will, under ordinary circumstances, remain closed.

25 In the accompanying drawings, Figure 1 is a side view of a bracelet embodying my improvements, and shown as closed. Fig. 2 is a side view of the same open. Fig. 3 is a transverse section of the bracelet, taken on the line 30 $x x$, Fig. 1. Fig. 4 is a sectional edge view of a portion thereof, on a larger scale, taken on the line $y y$, Fig. 1. Fig. 5 is a sectional edge view of portions of the meeting ends of the two parts of said bracelet. Fig. 6 is a perspective view of a modified form of bracelet embodying my improvements. Fig. 7 is a perspective view of another modified form of bracelet embodying the improvements. Fig. 8 is a transverse section of the latter bracelet; and 40 Fig. 9 is a sectional edge view of the meeting ends of the two parts of the latter bracelet.

Similar letters of reference designate corresponding parts in all the figures.

Referring first to Figs. 1, 2, 3, 4, and 5, it 45 will be seen that the bracelet there represented is composed of two parts, A and B, which are hinged together at one end and made to close at their other ends by the resilience of the sections of which they are composed. Each part 50 is composed of a comparatively thick and stiff

section, a , and two thinner resilient sections, b , arranged one on each side of the section a . The sections a of the two parts are not directly connected together; but the thinner resilient sections b of the part B are pivoted or hinged to 55 the section a of the part A, and thus the two parts A and B are connected together. It is important to observe that the resilient sections b of the part B are pivoted to the section a of the part A, one forward of the other, hence 60 when the parts A B are swung apart, or, in other words, opened, the sections b are spread apart, one forward and the other backward of the section a of the part B. The resilience of the sections b of the part B causes them to tend 65 to assume their normal positions, side by side, and this effects the closing or bringing together of the free ends of the parts A B of the bracelet. It is obvious that the parts of the bracelet themselves are made to form a spring or 70 springs for closing the free ends of the two parts of the bracelet, and that no independent spring is used or is necessary.

Referring now to Fig. 6, it will be seen that each part A B of the bracelet there shown is 75 made of two sections, $c d$, of spring or resilient material, and that the two portions $c d$ of the two parts A B are pivoted or hinged together at different points in the length of the bracelet. It is obvious that on swinging apart the 80 free ends of the parts A B of this bracelet the sections $c d$ are deflected in different directions, and through their resilience tend to bring the free ends of the parts A B together again.

85 Referring now to Figs. 7, 8, and 9, it will be seen that the part A is made of a solid piece of metal or other suitable material, and that the part B is split for a portion of its length. These split sections $e f$ are resilient, and are 90 pivoted or hinged to the part A at different points in the length of the bracelet. When the parts A B are swung apart the split sections are deflected in different directions, and their tendency to come together effects the return of the parts A B to their normal position.

All these bracelets which I have described may be made of metal or other suitable material.

It is obvious that by my improvements I dis- 100

pense with an independent spring and make the parts of the bracelet themselves form a spring or springs.

I do not limit myself to making bracelets in these ways, for many other articles may be made to constitute or comprise springs in the same ways.

It is not necessary that both the sections in any of the bracelets or other articles should be resilient.

What I claim as my invention, and desire to secure by Letters Patent, is—

1. The combination, in a bracelet or analogous article, of two parts, one of which com-

prises two sections, either or both being resilient, and which are pivoted or hinged to the other part at different positions in the length of the bracelet, substantially as specified.

2. The combination, in a bracelet or analogous article, of two parts, one of which comprises two resilient sections, which are pivoted or hinged to the other part at different positions in the length of the bracelet, substantially as specified.

E. JOHN M. BECKER.
